UNITED STATES PATENT OFFICE

HELEN DRYDEN, OF NEW YORK, N. Y., ASSIGNOR TO LADY ESTHER COMPANY, OF CHICAGO, ILLINOIS, A CORPORATION OF ILLINOIS

DESIGN FOR A JAR OR SIMILAR CONTAINER

Application filed November 4, 1931. Serial No. 41,616. Term of patent 3½ years.

To all whom it may concern:

Be it known that I, HELEN DRYDEN, a citizen of the United States, residing in New York, in the county of New York and State of New York, have invented a new, original and ornamental Design for a Jar or Similar Container, of which the following is a specification, reference being had to the accompanying drawing, forming a part thereof.

The drawing is the perspective of a jar or similar container.

I claim:

The ornamental design for a jar or similar container, as shown.

HELEN DRYDEN.
